UNITED STATES PATENT OFFICE.

OSCAR J. MARTINSON, OF CHICAGO, ILLINOIS, ASSIGNOR TO MONIGHAN MACHINE CO., A CORPORATION OF ILLINOIS.

EXCAVATOR-TRACTOR.

1,095,464.

Specification of Letters Patent.

Patented May 5, 1914.

Application filed April 1, 1913. Serial No. 758,160.

To all whom it may concern:

Be it known that I, OSCAR J. MARTINSON, a citizen of the United States of America, and a resident of Chicago, county of Cook, 5 and State of Illinois, have invented certain new and useful Improvements in Excavator Tractors, of which the following is a specification.

This invention relates to means for propelling excavating or other similar machines whereby they may be lifted and propelled with facility over unevennesses on ground surfaces, or propelled along soft ground.

The objects of the invention are to improve existing mechanism of this nature to decrease the amount of manual labor, time, and mechanical operations necessary for effecting the propulsion of excavating machines, derricks, etc.

20 An illustrative embodiment of this invention is shown in the accompanying drawings, in which:

Figure 1 is a side elevation of an excavating machine provided with traction mechanism. Fig. 2 is a fragmentary side elevation showing the traction mechanism as it would appear immediately before the machine is lifted from the ground in the operation of propelling it forward. Fig. 3 is a detail showing the manner of connecting the supporting cables to the auxiliary bases.

In applicant's copending application for patent Serial No. 756,473 filed March 24, 1913, there is shown and claimed propelling mechanism similar to the present mechanism in some general features. In each application there is shown an excavating mechanism rotatably mounted on a horizontally disposed circular base, together with rotating members capable of lifting the machine on its supports and moving it forward by a step by step motion. These rotating members coöperate with auxiliary bases or feet adapted to be engaged with the ground 45 while the machine is lifted and moved forward around pivotal bearing connections with such auxiliary bases. During such movement of the machine one side of said circular base may be permitted to drag over the earth and thereby assist in steadyng its respective machine. In the above mentioned copending application the auxiliary bases are shown pivoted to arms fixed to a rotating shaft, suitable means being provided for guiding the auxiliary bases so that

when in operation they will properly engage the ground. In the present case the auxiliary bases are supported independently of the means which engages them with the ground, and are automatically maintained 60 in a more or less horizontal position at all times while the propelling means is still rotary in character.

Referring to the drawings, the numeral 1 designates a housing for the operating 65 mechanism of a land dredge. This housing is mounted on a platform 2 supported by a central bearing 3 and side bearings on a turn table base member 4. The operating mechanism of the dredge includes connections for rotating the platform 2 on the base 4, as required for the specific operations of digging or dredging and for directing the entire machine when it is propelled over the surface of the ground. These 70 connections are customary in machines of the particular type shown in the drawings, and are therefore not described in detail.

The mast of the dredge is designated by the numeral 5, and leading around a sheave 6 on the mast and sheave 7 connected to boom 8 by a link 9 is the boom line 10. The free end of this line leads downwardly into the housing 1 and around a suitable controlling drum therein. A drag bucket 11 85 is hung from the boom 8 by a fall line 12. This line also leads to a power driven drum within the housing 1 and is operated in a well known manner. The drag line for bucket 11 is designated by numeral 13. The 90 boom 8 is pivoted to platform 2 by a pin 14 so that it may be raised or lowered by means of the boom line 10, but in order to swing the boom 8 from side to side it is necessary to rotate platform 2 and mechanism supported thereby around the base 4, and this operation is usually accomplished by an engine supported by the platform 2.

The foregoing general description relates to a well known type of land dredge. The 100 present invention has relation to the means for moving the dredge over the surface of the ground, and the dredge is designed to accomplish this end in a satisfactory manner when operating on all normal surface 105 conditions. It is capable of moving the machine over rocky and uneven ground, and also of supporting the machine on or moving it over comparatively soft surfaces. In its operation it lifts the dredge so that its 110

supporting base will be considerably above the ground at the side in the direction of movement, while the other side is permitted to trail over the surface of the ground and thereby assist in steadyng the machine in its movement.

The operating mechanism of the dredge includes a power shaft 15 journaled in bearings 16 secured to platform 2. At each end of shaft 15 and outside of housing 1 is an arm 17, rigidly secured to the shaft and provided at its ends with knobs 18 adapted on rotation of shaft 15 to alternately engage an auxiliary base 19, one of which is located at each side of the machine. The auxiliary bases 19 may be provided with central depressions 20 forming temporary seats for the knobs 18 when the device is in operation. The bases 19 are supported by cables 21 connected to eyes 22 on the said bases and passing around sheaves 23 pivoted on brackets 24 secured to platform 2. The ends of cables 21 are secured to weights 25. These weights serve to normally hold the auxiliary bases 19 in their upper positions in contact with stops 26. The arms 17 when not in operation normally lie in a substantially horizontal position, and therefore permit the auxiliary bases 19 to assume their upper positions in contact with stops 26. The shaft 15 is located at one side of the center of gravity of the dredge, in order that when the dredge is supported by shaft 15 in the propelling operation one end of base 4 may drag over the surface of the ground and assist in steadyng the machine. The shaft 15 is also not centrally located between sheaves 23, but is in such position that the knobs 18 on arms 17 will contact with depressions 20 in auxiliary bases 19 when the arms are about in the angular position indicated in Fig. 2. This arrangement results in the dredge being propelled forward by swinging it around a fulcrum formed between depressions 20 and knobs 18 during the rotation of shaft 15.

In the operation of a dredge of this nature it is necessary to frequently move the same in the direction in which the work is progressing. The bucket to be filled is lowered and then dragged toward housing 1. It is then as a rule hoisted and swung to one side and emptied. After the ground has been excavated to a sufficient extent in this manner the machine is moved forward, but it is not necessary to stop the work of excavating in order to so move the machine. All that is required of the operator is to clutch shaft 15 with engine driven mechanism, and thereby cause the same to rotate in the direction indicated by arrow 27 (Fig. 2). Such rotation of shaft 15 causes the knobs 18 on the arms 17 to alternately engage the auxiliary bases 19, and thereby force the same downwardly into contact

with the ground as indicated in Fig. 2. As the knobs 18 engage the auxiliary bases 19 to the left of their centers of gravity (Fig. 2), the forward ends 28 of the bases will engage the ground first and then their rear ends 29 will rock downwardly until the bases are entirely in contact with the ground. By this time the knobs 18, which are in engagement with the auxiliary bases, arrive at the depressions 20, and the further rotation of shaft 15 causes the entire dredge including base 4 to be lifted off the ground and carried in a forward direction, as indicated by the arrow 30 (Fig. 2), around a fulcrum formed between the lower knobs 18 and the depressions 20. During this rocking movement of the dredge the rear side of base 4 is permitted to drag over the ground, as indicated in Fig. 1. When the base again rests evenly on the ground the knobs 18 rise out of depression 20, and the auxiliary bases 19 follow the knobs until stopped by the stops 26. The operation is continued in this manner until the dredge has been propelled forward the required extent. The auxiliary bases 19 have both up and down movements and horizontal movements with respect to the dredge, as when the dredge is rocked forward the auxiliary bases are held against movement by contact with the earth, and when released by arms 17 swing forward, hinging from sheaves 23, to their normal position. The direction of traveling movement of the dredge is controlled by turning the same in a horizontal plane on its pivotal connection 3 with base 4.

It will thus be seen that the present invention provides auxiliary supports or bases for land dredges and similar machines which are operated by rotary devices to co-operate with the main support of the dredge for causing it to travel forward, these rotating devices operating to engage the auxiliary supports with the ground and also to then move the dredge relatively to the auxiliary supports and thereby propel it over the ground.

While mention is made herein that one side of the base 4 may be permitted to drag over the ground while the machine is traveling, and thereby assist in steadyng the machine, it may be noted that this is not necessary as the base 4 may be lifted entirely clear of the ground, for example as would be desirable when a plurality of propelling devices are provided in each machine.

Although but one specific embodiment of this invention has been herein shown and described, it will be understood that numerous details of the construction shown may be altered or omitted without departing from the spirit of this invention as defined by the following claims.

I claim:

1. In a device of the class described, the combination of a base, a body carried thereby, auxiliary bases carried by said body at opposite sides of said base, counterweights connected to said auxiliary bases and adapted to normally lift the same clear of the ground, and operating means carried by said body and movable into and out of contact with said auxiliary bases and adapted to force the same into contact with the ground for propelling the machine along the ground.
2. In a device of the class described, the combination of a base, a body carried thereby, auxiliary bases carried by said body at opposite sides of said base, cables attached to said auxiliary bases and being counterweighted for normally lifting said auxiliary bases clear of the ground, and operating means carried by said body and movable into and out of contact with said auxiliary bases and adapted to force the same into contact with the ground for propelling the machine along the ground.
3. In a device of the class described, the combination of a base, a body carried thereby, auxiliary bases carried by said body at opposite sides of said base, operating means carried by said body and movable into and out of contact with said auxiliary bases and adapted to force the same into contact with the ground for propelling the machine along the ground, counterweighted cables attached to said auxiliary bases and adapted to normally lift the same clear of the ground, and stops for limiting the upward movement of said auxiliary bases.
4. In a device of the class described, the combination of a base, a body carried thereby, auxiliary bases carried by said body at opposite sides of said base, means adapted

to normally lift said auxiliary bases clear of the ground, stops provided with antifriction devices adapted to limit the upward movement of said auxiliary bases while permitting them to shift horizontally, and operating means carried by said body and movable into and out of contact with said auxiliary bases and adapted to force the same into contact with the ground for propelling the machine along the ground.

5. In a device of the class described, the combination of a base, a body carried thereon, auxiliary bases carried by said body at opposite sides of said first named base, means normally lifting said auxiliary bases, stops limiting the lifting of said bases, and rotatable arms adapted to engage said auxiliary bases for shifting the same into contact with the ground and propelling the device, said auxiliary bases having sockets adapted to serve as seats for said arms.

6. In a device of the class described, the combination of a base, a body carried thereon, auxiliary bases carried by said body at opposite sides of said first named base, means normally lifting said auxiliary bases and adapted to normally urge the same horizontally to a certain predetermined position with respect to said first mentioned base, stops limiting the lifting of said bases, and rotatable arms adapted to engage said auxiliary bases for shifting the same into contact with the ground and propelling the device, said auxiliary bases having sockets adapted to serve as seats for said arms.

Signed at Chicago this 26th day of March 1913.

OSCAR J. MARTINSON.
